UNITED STATES PATENT OFFICE.

HENRY B. LAHR, OF NEW YORK, N. Y., ASSIGNOR OF ONE-HALF TO
BOWLING BALL COMPANY, OF NEW YORK, N. Y., A CORPORATION
OF NEW YORK.

BOWLING-ALLEY.

SPECIFICATION forming part of Letters Patent No. 709,163, dated September 16, 1902.

Application filed January 27, 1902. Serial No. 91,322. (No model.)

To all whom it may concern:

Be it known that I, HENRY B. LAHR, a citizen of the United States, and a resident of the borough of Manhattan, in the city and State 5 of New York, have invented a new and useful Improvement in Bowling-Alleys, of which the following is a specification.

My invention relates to an improvement in bowling-alleys, and has more particularly for 10 its object to provide a bowling-alley having a runway extending lengthwise of the alley, the said runway having an inclined portion at its rear end and a substantially horizontal portion leading therefrom to its front end and a 15 separate transverse runway located across the rear end of the alley in position to permit the ball to drop therefrom onto the inclined portion of the longitudinal runway.

A further object is to provide a device of the 20 above character whereby the balls may be delivered to the front end of the runway accurately at a predetermined speed irrespective of the speed with which they are started by the "pin-boy."

25 A practical embodiment of my invention is represented in the accompanying drawings, in which—

Figure 1 shows a bowling-alley in plan comprising six alleys. Fig. 2 is a transverse vertical section taken in the plane of the line A A of Fig. 1 looking in the direction of the arrows. Fig. 3 is a longitudinal vertical section taken in the plane of the line B B of Fig. 30 1. Fig. 4 is an enlarged detail view in perspective of the adjacent ends of the transverse runway and the longitudinal runway, together with the stop for insuring the balls dropping from the transverse runway onto the said longitudinal runway.

40 The longitudinal runway extending lengthwise of the alleys is herein shown as comprising an inclined portion 1 at its rear end and a substantially horizontal portion 2, extending from the base of the incline to the forward end of the runway. This runway is further shown as provided at its forward end with a laterally-extended branch 3, serving to bring the balls into a convenient position for the bowlers at the front or delivery end of the 45 50 alley. The inclined portion 1 may be so arranged that it will give the required impetus

to the ball when dropped thereon to cause the ball to roll to the front end of the runway at the required speed. A transverse runway is located across the rear or back end of the 55 alley, and it is arranged in position to cause the ball when it rolls therefrom to drop onto the inclined portion 1 of the longitudinal runway. A stop or buffer 5 is spaced from the delivery end of the transverse runway 4 in 60 position to receive the impact of the ball as it runs along the said transverse runway and insure the dropping of the ball onto the inclined portion of the longitudinal runway. This stop 5 is preferably of angular form, as 65 shown, and it is of sufficient size to prevent the ball from bounding off the longitudinal runway when it is dropped thereon. The receiving end of the transverse runway 4 may be left open, if so desired, for facilitating the 70 throw of the balls thereinto by the pin-boys. This transverse runway 4 preferably has a slight downward inclination, so as to insure the rolling of the balls along the same down to the delivery end of the said transverse runway. This transverse runway 4 may be made of any desired length, so as to extend across 75 one or more of the alleys.

In the accompanying drawings I have shown six alleys with two oppositely-directed 80 transverse runways for dropping the balls onto the inclined portions of two longitudinal runways, the front ends of the said longitudinal runways being turned laterally toward each other for bringing the balls into convenient reach of the bowlers. It is to be understood that these alleys may be supported in any desired manner, that shown herein being a plurality of supporting-posts 6 for the longitudinal runways and supporting-posts 7 85 90 for the transverse runways.

It will be seen that this construction obviates the necessity of an incline for the balls at the forward end of the runway, for the reason that the ball will always be dropped 95 onto the inclined portion of the longitudinal line at a predetermined speed entirely irrespective of the speed with which the pin-boy delivers the ball into the transverse runway.

The inclined portion 1 of the runway may 100 be formed at a sufficient degree of inclination to insure the delivery of the balls at the

front end of the longitudinal runway at such a low speed as to preclude the possibility of nicking the balls.

It is evident that changes might be resorted to in the form, construction, and arrangement of the several parts without departing from the spirit and scope of my invention. Hence I do not wish to limit myself strictly to the structure herein set forth; but

10. What I claim is—

1. In a bowling-alley, a runway extending lengthwise of the alley and having an inclined portion at its rear end and a separate transverse runway located across the rear end of the alley and arranged to permit the ball to drop therefrom onto the incline of the longitudinal runway, substantially as set forth.

2. In a bowling-alley, a runway extending lengthwise of the alley and having an inclined portion at its rear end and a substantially horizontal portion leading therefrom to its front end and a separate transverse runway located across the rear end of the alley and arranged to permit the ball to drop therefrom onto the inclined portion of the longitudinal runway, substantially as set forth.

3. In a bowling-alley, a runway extending lengthwise of the alley and having an inclined portion at its rear end, a separate transverse runway located across the rear end of the alley and arranged to permit the ball to drop therefrom onto the inclined portion of the longitudinal runway and a stop arranged in position to cause the ball to drop onto the said longitudinal runway, substantially as set forth.

4. In a bowling-alley, a longitudinal runway, a branch runway leading laterally therefrom at the front end of the alley and a separate transverse runway located across the rear end of the alley and arranged to permit the ball to drop therefrom onto the longitudinal runway, substantially as set forth.

In testimony that I claim the foregoing as my invention I have signed my name, in presence of two witnesses, this 22d day of January, 1902.

HENRY B. LAHR.
